UNITED STATES PATENT OFFICE

107,317

DESIGN FOR A REFRIGERATING MOLD

Jose H. de Murguiondo, Washington, D. C.

Application October 21, 1937, Serial No. 72,353

Term of patent 7 years

To all whom it may concern:

Be it known that I, Jose H. de Murguiondo, a citizen of the United States, residing at Washington, District of Columbia, have invented a new, original, and ornamental Design for Refrigerating Molds, of which the following is a specification, reference being had to the accompanying drawing, forming part thereof.

The figure is a perspective view of a refrigerating mold, showing my new design.

I claim:

The ornamental design for a refrigerating mold, as shown.

JOSE H. DE MURGUIONDO.
